PNEUMATIC CLASSIFIER

Martin Frisch, New York, N. Y., assignor to Foster Wheeler Corporation, New York, N. Y., a corporation of New York

Application March 30, 1932, Serial No. 601,916

6 Claims. (Cl. 209—144)

My invention relates to classifiers for classifying finer or lighter particles of material from the coarser or heavier particles which may be suspended or carried in a current of air and more particularly to classifiers for use in connection with coal pulverizers.

The primary object of my invention is the construction of an apparatus of the type above described which shall be adapted to continuously receive large volumes of air and pulverized material without any substantial interruption in flow therethrough while at the same time effectively eliminating heavier particles therefrom.

A second object of my invention is to provide an apparatus of the type described which shall be adapted to be bolted or otherwise secured directly to the inlet of the exhauster or fan used to induce air through the pulverizer and classifier so that the classifier and fan may together cooperate to form a self contained unit with no intermediate connections between them.

A further object of my invention is to so construct the classifier that the heavier particles which become separated do not pass through the path of flow of the air and pulverized material during the separation process.

My classifier is particularly desirable for use with an air swept pulverizing mill which is used for pulverizing coal to be supplied directly to a furnace. To this end, I have provided means associated with the classifier for admitting additional air for combustion of the pulverized coal, as well as for controlling the velocity and volume of air sweeping the mill.

Other objects and advantages of my invention will be made clear upon consideration of the following description of a preferred embodiment thereof taken in conjunction with the accompanying drawing, which forms a part of this specification and of which:

Fig. 1 is a side view, partly in elevation and partly in cross-section, of a preferred embodiment of the invention;

Fig. 2 is a cross-sectional view taken along line 2—2 of Fig. 1;

Fig. 3 is a diagrammatic view showing the arrangement of the classifier at the discharge end of a ball type pulverizing mill; and

Fig. 4 is a diagrammatic view showing the classifier attached directly to the fan casing.

The classifier, designated generally by numeral 10, is mounted on the floor or foundation 12 by means of supports 11. The classifier includes an outer casing comprising vertical end walls 13 and 20 between which extend an upper curved wall

portion 17 which is essentially semi-cylindrical and is curved on a given radius about the center line *a*, which center line constitutes the axis of the classifier, and which is horizontal. An upwardly directed inlet 14 is formed by wall portions 41, 42, 43, and a part of end wall 19. Wall portions 41 and 17 are continuations of each other, wall portion 41 being tangential to wall portion 17. A pocket 32 is formed by downwardly converging wall portions 44, 45, 46, and 47. The wall portion 45 meets wall portion 42, and wall portion 44 is tangential to and a continuation of wall portion 17.

Within the outer casing is an inner wall member 18 with respect to which wall portion 42 is a continuation and is tangential. Wall member 18 is drawn about the axis *a* concentric with the outer side wall portion 17. A part of wall member 18 is pivoted at 48 and forms a damper 26 presently to be explained. Wall member 18 extends from wall portion 42 over the top of the center line *a* and terminates short of a complete circle providing a lower opening for the central partial cylindrical chamber 50 formed by member 18 and the end walls.

Between the outer wall portion 17 and the inner wall member 18 is formed a partial annular passage 21 extending over the top of the inner wall member 18. Just above the bottom 32 is what may be termed an expansion chamber 22. In the end of chamber 50 is an opening to which is connected a discharge conduit 16 concentric with the classifier axis *a*. This discharge conduit leads to a fan which conducts air laden with pulverized coal to a furnace or to storage.

On the top of the classifier is a port 29 over which is a plate 30. A damper or plate valve 31 is pivoted at one side of this port or opening at 52 and is arranged to be swung downwardly so as to extend across passage 21. In its uppermost position, member 31 closes port 29. Port 29 affords connection with the atmosphere for introducing fresh air into the classifier. The position of member 31 is controlled manually by means of a lever 53 and a set screw or wing nut 54.

The damper 26 is adjustable by means of lever 27 and wing nut 28. As can be seen from Fig. 1, this member can be swung upwardly so as to close or substantially close the passage 21. It will be seen that, as this member is moved upwardly, it affords a restricted outlet from passage 21 into the expansion chamber 22. If, on the other hand, this member is swung to the left of the position shown in full lines in Fig. 1, it

forms an enlarged discharge portion for the passage 21 into the chamber 22.

A deflecting plate 23 is mounted at 55 along-
5 side the wall portion 45 and can be swung up-
wardly toward damper 26. This member 23
serves to vary the effective volume of chamber
22.

Pocket 32 discharges downwardly into an air
lock 34. This is a device for permitting coal or
10 other pulverized material to pass therethrough
while preventing, or substantially preventing the
passage of air. The air lock may be constructed
as shown with a plurality of vanes 35 mounted
15 on a shaft in a cylindrical casing and driven
from an electric motor 40 and reduction gearing
56. The air lock discharges into a conduit 33
which is connected with the coal inlet side of
the pulverizing mill.

Referring to Fig. 3, which shows one organiza-
20 tion view including my improved classifier, air
is supplied to the mill by conduit 60 and coal at
61. The supply of air may be controlled by a
damper 62. Auxiliary air may be supplied at 63.
The air passes through the mill, leaving by the
25 conduit 65 which connects to the inlet 14 of the
classifier.

The operation of the classifier is as follows:

Assuming that the valve members 31, 26, and
23 are in the positions shown in full lines in
30 Fig. 1, the fan F acts to draw air laden with
pulverized coal from the mill through conduit 65
and into the inlet 14. Thence the air laden with
coal passes through the passage 21 and into
35 chamber 22. The passage 21 is arcuate and the
curvature of this passage gives a centrifugal
force effect to the coal. However, while I prefer
a smooth passage, as shown, this is not necessary
so long as the air passage over the top of the
40 member forming the central chamber is given a
curved path. The coal being directed downward-
ly as it enters the expansion chamber 22, the
heavier particles will keep on going downwardly
while the air will carry the lighter particles up-
wardly into chamber 50 and thence into the fan
45 which may deliver the pulverized coal and air to
a furnace. It will be noted that the heavier par-
ticles are given a direction away from the main
stream and that the heavier particles do not
cross the main stream in passing to the pocket
50 32. It will be seen that the inlet 14 is tangential
to the passage 21 which affords a smooth entry
of fluid into the classifier and avoids separation
until the stream reaches the expansion chamber.
It will be noted that the flow is spiral, working
55 inwardly toward the center a, and that the dis-
charge is axial at the center line.

If, now, the valve member 31 is moved to the
position shown in dash-and-dot lines in Fig. 1,
will be seen that flow from the mill through con-
duit 65 is cut off and the fan may draw only
60 fresh air through the port 29. Consequently, it
will be apparent that by adjusting the valve
member 31 to any intermediate position, any de-
sired ratio of fresh air to coal laden air may be
65 obtained.

It will be understood that the member 31 will
vary the proportion of coal laden air to fresh
air, but it will not control the amount of air
passing through the fan. This, however, may
70 be accomplished by the valve member 26 which
is adapted in the position shown in dash-and-dot
lines in Fig. 1 to substantially close the passage
21. This member may be placed in an interme-
diate position so as to give a high restricted dis-
charge into chamber 22 along the wall portion 44.

It will be clear that this will increase the velocity
of the coal and the air and will cause a larger
degree of precipitation of coal particles. Thus,
the fineness can be regulated. The plate 23 may
be moved to control the effective volume of the
5 chamber 22 and by moving this plate upwardly
and fixing the damper 26 in a more inward position,
the mixture can be made to contain more
of heavier particles.

The change of velocity and direction of flow of 10
the air and pulverized material as it enters the
expansion chamber 22 are the factors which
cause separation of the oversize therein. The
particles of desired fineness float out through the
central discharge conduit 16 to the point of use, 15
while the heavier particles or oversize drop into
the chamber 32.

The oversize which collects in chamber 32 is
returned by gravity through conduit 33 to the
20 feed end of the mill 15 for further pulverization.
Obviously, however, the oversize may be returned
to any part of the mill. An air lock or trap 34
has been inserted in conduit 33 to improve the
25 efficiency of the classifier and to facilitate the
operation of the gravity return. It is obvious
that by merely adjusting the elements 23, 26,
and 31 it is possible to get any desired degree of
separation without altering the speed of the ex-
haust fan.

One of the important features of my invention 30
is that at no time does the oversize, which has
been separated out, have a chance to reenter or
cross the path of the moving stream. This fact
aids materially in improving the efficiency of my
35 classifier since no power is wasted in pulling the
cloud of dust through a screen formed by over-
size dropping through the stream. Furthermore,
the separation is more effective since there is no
chance for the oversize to be picked up again and
carried out of the classifier.

It is also important to observe that the flow
40 of pulverized material and air through the classi-
fier is smooth and substantially uninterrupted,
which fact makes it possible to sweep the pul-
verizing mill with large volumes of air without
45 excessive power consumption by the fan and
without making the classifier unduly large in
size.

Fig. 4 shows the preferred combination of fan
F and classifier 10 wherein the fan is imme-
50 diately adjacent the classifier, the outlet of the
classifier being attached directly to the inlet of
the fan as by bolts 68. In this case the fan
may be said to be supported on the classifier or
in any event there is a rigid connection with
55 a short conduit between the classifier and the
fan whereby the two are in effect one unitary
structure. This arrangement is advantageous in
saving space.

Suitable access doors may be advantageously 60
provided in the side wall of the classifier.

While my invention involves various novel fea-
tures, it is to be understood that in some cases
certain features of my invention may be used
65 to advantage without a corresponding use of
other features and yet fall within the scope of
the invention, and that the invention is not
limited to the embodiment disclosed, but is to
be limited only by the scope of the appended
claims.

What I claim is:

1. A classifier comprising a casing including
end walls and an outer curved wall portion con-
necting the end walls, an inner wall member,
said outer wall portion and said inner wall mem- 75

- ber being curved about a horizontal axis and providing a central chamber open at the bottom and a curved passage extending over the top of the inner member, means to supply fluid to said curved passage tangentially of the classifier, an auxiliary air supply opening in said curved passage, and a member in said curved passage movable to vary flow therethrough and to vary flow through said auxiliary opening.
5. A classifier comprising a casing including end walls and an outer curved wall portion connecting the end walls, an inner wall member, said outer wall portion and said inner wall member being curved about a horizontal axis and providing a central chamber open at the bottom and a curved passage extending over the top of the inner member, means to supply fluid to said curved passage tangentially of said classifier, an auxiliary air supply opening in said curved passage, a member in said curved passage movable to vary flow therethrough and to vary flow through said auxiliary opening, and a movable member for controlling the relation of flow into said pocket and said central chamber.
10. 2. A classifier comprising a casing including end walls and an outer curved wall portion connecting the end walls, an inner wall member, said outer wall portion and said inner wall member being curved about a horizontal axis and providing a central chamber open at the bottom and a curved passage extending over the top of the inner member, means to supply fluid to said curved passage tangentially of said classifier, an auxiliary air supply opening in said curved passage, a member in said curved passage movable to vary flow therethrough and to vary flow through said auxiliary opening, and a movable member for controlling the relation of flow into said pocket and said central chamber.
15. 3. A spiral centrifugal classifier having its axis horizontal and comprising an upwardly extending inlet, a partial annular passage connected therewith for directing flow downwardly, an expansion chamber for receiving flow directed downwardly by said passage, means in said passage for varying the proportion of pulverized material to air flowing therethrough, a damper for varying the velocity of flow into said expansion chamber, means for varying the effective volume of said expansion chamber, and a central discharge conduit having an axis coinciding with the axis of the classifier.
20. 4. A classifier comprising a casing arranged to provide a smoothly curving passage about a horizontal axis discharging in a vertically downward direction into an expansion chamber in the casing, the classifier having an outlet disposed above the expansion chamber, the walls defining the curving passage being arranged so as to prevent the collection of material in flowing through the passage to the outlet and to prevent the passage of separated material into or through the normal path of flow through the classifier to the outlet, one of the walls defining the passage having an air opening, means comprising a damper operative to control said air opening and the flow area of the passage to vary the proportion of material and air flowing through the passage, and means comprising a damper in the expansion chamber for controlling the effective volume of the expansion chamber to control the fineness of the particles of material separated from the stream of material flowing through the passage.
25. 5. A classifier comprising a casing arranged to provide a smoothly curving passage about a horizontal axis discharging in a vertically downward direction into an expansion chamber in the casing, the classifier having an outlet disposed above the expansion chamber, the walls defining the curving passage being arranged so as to prevent the collection of material in flowing through the passage to the outlet and to prevent the passage of separated material into or through the normal path of flow through the classifier to the outlet, one of the walls defining the passage having an air opening, means comprising a damper operative to control said air opening and the flow area of the passage to vary the proportion of material and air flowing through the passage, and means comprising a damper in the expansion chamber for controlling the effective volume of the expansion chamber to control the fineness of the particles of material separated from the stream of material flowing through the passage.
30. 6. A classifier comprising a casing arranged to provide a smoothly curving passage about a horizontal axis discharging in a vertically downward direction into an expansion chamber in the casing, the classifier having an outlet disposed above the expansion chamber, the walls defining the curving passage being arranged so as to prevent the collection of material in flowing through the passage to the outlet and to prevent the passage of separated material into or through the normal path of flow through the classifier to the outlet, one of the walls defining the passage having an air opening, means comprising a damper operative to control said air opening and the flow area of the passage to vary the proportion of material and air flowing through the passage, and means for controlling the flow area of the passage to control the velocity of flow of material therethrough and into the expansion chamber, and means for controlling the effective volume of the expansion chamber.

MARTIN FRISCH.
